UNITED STATES PATENT OFFICE

2,647,465

DEVICE TO RESIST THE DISARMING OF BOMBS

Jacob Rabinow, Takoma Park, Md., assignor to the United States of America as represented by the Secretary of the Army

Application June 3, 1952, Serial No. 291,583

3 Claims. (Cl. 102—70)

(Granted under Title 35, U. S. Code (1952), sec. 266)

1

The invention described herein may be manufactured and used by the Government for governmental purposes without the payment to me of any royalty thereon.

This invention relates to bomb fuses and more particularly to means for preventing the successful disarming of bombs and bomb fuses or the like.

Where bombs which have been dropped on enemy targets fail to detonate, extensive efforts are generally made by enemy personnel to disarm the bombs without causing detonation. One of the more common means of disarming a bomb is to drill a small hole into the fuse cavity and pour therein a disabling liquid which may be an acid or a material which will solidify around the moving elements. In order to make disarming by drilling impossible, I have devised a means wherein variations in pressure between chambers in the fuse will cause detonation of the bomb. My device may be used in under water as well as in surface missiles.

The specific nature of the invention as well as other objects and advantages thereof will clearly appear from the following description and accompanying drawings in which:

Figure 1 is a longitudinal sectional view showing an embodiment of the invention incorporated in a point detonating fuse affixed to a general purpose bomb.

Figure 2 is a cross sectional view taken generally along lines 2—2 of Figure 1.

Figure 3 is an enlarged cross sectional view of a pressure equalizing means.

Figure 4 is a schematic wiring diagram of the invention.

Referring now to Figure 1 of the drawings wherein 1 indicates a bomb casing having an explosive charge 2 therein and 3 indicates a point detonating type of fuse threadedly affixed in the nose 4 of the bomb. A cavity 5 is formed in the body of the fuse which in combination with a base plate 6 forms a hermetically sealed chamber 11. The base plate is sealed to the body as by soldering to a shoulder 7 formed in the longitudinal walls 8 of the cavity 5 adjacent the open end 9. A booster 10 is conventionally assembled to the fuse at the open end 9. Chamber 12 is formed within the chamber 11 by means of a cylindrical member 13 in sealed, threaded engagement with a recess 14 formed in the wall 8 as indicated by reference numeral 15. The end of cylindrical member 13 is provided with diaphragm 16. The diaphragm 16 is coupled to blade 17 of a single pole double throw switch 21.

The blade being positioned between oppositely disposed contacts 19 and 20 supported and connected by means of a U-shaped member 21a which is affixed to wall 8 in insulated relationship thereto. A pressure equalizing means 23 is formed integral with the cylindrical member 13 and consists of an orifice 22 extending through the wall of the cylindrical member and surrounded on the outside surface of the wall by means of a nipple 23a formed therewith. The nipple houses a ceramic plate 24, which is held therein by means of a cap member 25 in threaded engagement with the nipple. An orifice 26 in the cap member is in alignment with the orifice 22. Member 24a is a gasket surrounding the edge of the ceramic 24. A valve 27 for admitting air to chamber 12 is affixed in that portion of wall 8 which forms one closed end of the cylindrical member 13. A valve 28 is also affixed in the wall 8 for admitting air to chamber 11. The nose member 3 has formed therein a longitudinal bore 29. Coextensive with bore 29 is a tubular member 30. The forward end of member 30 is sealed in the nose member 3 as at 31 in any conventional manner, and the opposite end 32, containing a detonator 33, is sealed in a perforation 34 in plate 6 in any conventional manner, for example, as by soldering at 35. A striker 36 positioned in bore 29 and tube 30 is releasably maintained therein in alignment with detonator 33 by means of shear pin 37. An electric detonator 38 is sealed in a perforation 39 in plate 6 by means of any of the well known sealing compounds. A trembler switch 46 positioned in a recess 46a and an inertia switch 40 is positioned in recess 41 of the nose member 3, both extending interiorly of the chamber 11. A battery 45 in the chamber 11 may be held therein by its opposite ends in recesses 42 and 43 formed in the interior surfaces of the nose 3 and plate 6, respectively.

Figure 4 is a wiring diagram showing the battery 45, inertia switch 40, detonator 38 and switch 21 in series connection with the trembler switch 46 shunted across switch 21.

Before the fuse is assembled to the explosive missile, chambers 11 and 12 are either equally pressurized or partially evacuated. Under either condition the blade 17 is out of contact with the contacts 19 and 20. If the striker fails to function the detonator 33 or any other means designed for normal functioning of a fuse fails to cause detonation of the bomb, such as timing means incorporated in certain fuses, any attempt to disarm the bomb by the aforementioned drilling method will cause loss of pressure in either

the chamber 11 or 12. Assuming that the drill enters chamber 11, the air pressure will be reduced therein due to air escaping through the drilled hole will result in diaphragm 16 moving the blade 17 into contact with contact 19 thereby closing the circuit and functioning the detonator 38. If the drill should enter chamber 12 the diaphragm will move inwardly of the chamber and cause blade 17 to close the circuit through engagement with the contact 20.

The inertia switch 40 is operative upon impact of the bomb and target to connect the battery in the circuit. The trembler switch 46 is included in the embodiment as an anti-disturbance means which will close the circuit and cause detonation if any attempt is made to remove the bomb.

Figure 3 is an enlarged cross sectional view of the pressure equalizing means. The ceramic member 24 will allow air to leak therethrough, either from the chamber 12 or the chamber 11 and thereby maintained equal air pressure in the chambers. The orifices 26 and 22 in the cap and wall, respectively, admit air to the ceramic element 24.

It will be apparent that the embodiment shown is only exemplary and that various modifications can be made in construction and arrangement within the scope of the invention as defined in the appended claims.

I claim:

1. Means to resist disarming of a bomb of the character described comprising a hermetically sealed container within the bomb, a second hermetically sealed container within the first mentioned container, each of said containers being equally pressurized, pressure equalizing means incorporated in said second container for maintaining equal pressure in each container, a double acting switch mounted on the interior surface of the first mentioned container, a diaphragm comprising one wall of the second container, the moving element of the switch operatively connected to the diaphragm, the diaphragm causing said switch to close an electric circuit containing a detonator when there is a

substantial difference in pressure in either container.

2. The invention in accordance with claim 1 wherein said pressure equalizing means comprises a ceramic plate hermetically sealed in a wall of the second container, one face of the plate being exposed to the interior of second container, the opposite face of the plate being exposed to the interior of the first mentioned container, said plate providing a slow leak means whereby any incidental pressure difference developed in either container will cause air to flow through said plate to the container of lower pressure.

3. The combination of a bomb fuse and means to prevent disarming thereof, said combination comprising a fuse body housing detonation mechanism, a hermetically sealed chamber within the body, a hermetically sealed container affixed to an interior wall of the chamber, the chamber and container being equally pressurized, breather means integral with the container to normally maintain pressure equilibrium in the chamber and container, a diaphragm comprising an end member of the container, a double acting switch mounted on said wall, the moving element of said switch linked to the diaphragm, a detonator affixed in the base of the chamber, and power supply means, said switch detonator and power supply means forming a detonator firing circuit, an anti-disturbance means in shunt with said switch, said diaphragm operative in response to a pressure differential of magnitude greater than normal to close the switch and cause the detonator to function.

JACOB RABINOW.
